UNITED STATES PATENT OFFICE.

ABRAHAM G. FELDMAN, OF CHICAGO, ILLINOIS.

DESIGN FOR A BED.

Application filed September 10, 1928. Serial No. 28,104. Term of patent 3½ years.

To all whom it may concern:

Be it known that I, ABRAHAM G. FELDMAN, a citizen of the United States, residing at Chicago, in the county of Cook and State of Illinois, have invented a new, original, and ornamental Design for a Bed, of which the following is a specification, reference being had to the accompanying drawing, in which a perspective view of the design is shown.

I claim:

The ornamental design for a bed, as shown. In testimony whereof I affix my signature.

ABRAHAM G. FELDMAN.
